(57) **CLAIM**

The ornamental design for a retail fixture, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top front perspective view of a retail fixture showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top front perspective view of a retail fixture showing the claimed design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The dashed broken lines in the figures show portions of the retail fixture that form no part of the claimed design.

FIGS. 1-7 and 8-14 are illustrated to show color. The colored portions and the white claimed portions of the retail fixture have an appearance as shown. The appearance of the white unclaimed portions of the retail fixture forms no part of the claimed design.

(Continued)

The gray background in FIGS. 1-7 and 8-14 is used to better illustrate the colored appearance of the retail fixture. The gray background itself forms no part of the claimed design.
